UNITED STATES PATENT OFFICE.

WILLIAM P. FORNFINNE, OF BROOKLYN, NEW YORK.

CHIP-HOLDER.

1,039,112.

Specification of Letters Patent. Patented Sept. 24, 1912.

Application filed July 8, 1911. Serial No. 637,462.

To all whom it may concern:

Be it known that I, WILLIAM P. FORNFINNE, a citizen of the United States, residing at Brooklyn, in the county of Kings and 5 State of New York, have invented new and useful Improvements in Chip-Holders, of which the following is a specification.

This invention relates to improvements in holders for butter chips, the object of the 10 invention being to provide a device of this character wherein the chip may be readily inserted or removed, the device comprising substantially a bowl of a cone-shaped formation having its sides channelled or otherwise depressed to accommodate the fingers 15 of the attendant in removing the chip from the bowl, the chip being also positioned above the bottom of the bowl to provide a receptacle or chamber for ice.

With the above objects in view, and others 20 which will appear as the nature of the invention progresses, the improvement resides in the novel construction and arrangement of parts hereinafter fully described and 25 claimed.

In the drawings, accompanying this specification, there has been illustrated a simple and approved chip holder constructed in accordance with the present invention, and in 30 which drawings—

Figure 1 is a perspective view of the improved chip holder. Fig. 2 is a vertical longitudinal sectional view showing the chip in position within the holder.

As is well known, the cubes or squares of butter are either served upon individual chips or upon a platter containing a sufficient number of chips for the occupants of the table. In the latter case, the platter occupies a large space which would otherwise have been occupied by various other dishes. In the first instance, the butter upon the chip may not be sufficient for the requirements of the eater and he is forced to call 35 upon the waiter for more butter. Besides, the butter upon the chip being subjected to the heat of the room is liable to melt before being used by the eater. In the latter instance, the cubes of butter are also susceptible to melting and the platter is, as aforesaid, of such a size as to occupy too large a space upon the table.

In the drawing, the numeral 1 designates my improved chip holder. This holder 1 45 embodies essentially a bowl 2, the latter be-

ing of a substantially cone-shaped formation, and the sides of the bowl are provided at intervals with outwardly depressed portions forming grooves or channels 3. These grooves 3 are arranged at an inclination similar to the body of the bowl 2, and arranged within the said bowl and contacting the sides thereof, so as to be sustained away from the bottom 4 of the said bowl, is a chip holding plate or disk 5. The space 60 between the chip disk 5 and the bottom 4 is adapted to provide a chamber for the reception of shaved or broken ice, as indicated by the numeral 6, and the disk itself is of course adapted to contain cubes of butter. The 65 improved holder may be constructed of any desired or approved material, and the said holder has its bottom 4 provided with a downwardly extending stem 7, the said stem 70 terminating upon a suitable base 8. 75

By an arrangement, as above stated, it will be noted that the outwardly extending grooved portions 3 provide means whereby the attendant may readily insert his fingers so as to remove the chip 5 from the bowl 2, 80 and at the same time the said grooves provide means whereby water from the chamber 6 may find egress when the device is tilted without necessitating the removal of the disk 5. In this instance, a suitable closure 85 is placed over the open top of the bowl to prevent the cubes of butter as well as the top from being removed from the bowl.

It is to be understood that the holder comprises a substantially small article and that 90 the grooves or channels 3 are arranged in pairs which are diametrically opposite each other, the space between the pairs of depressions being only great enough to permit of the forefinger and thumb of the attendant 95 passing therein to engage with and remove one of the butter chips from the chip holding disks 5.

The device is constructed so as to occupy only a small space upon the table, and the 100 simplicity of the construction, as well as the advantages thereof, will, it is thought, commend themselves to those skilled in the art to which such inventions appertain without further detailed description. 105

Having thus fully described the said invention, what I claim is:

A chip holder comprising a base having a stem and a cone-shaped bowl connected with the stem, the said bowl adapted to re- 110

ceive a chip sustaining disk and to provide an ice chamber between the bottom of the chip and the bottom of the bowl, the said bowl having its inner face formed with 5 finger depressions, the said depressions being arranged in pairs which are diametrically opposite each other, and one of the pairs of depressions being arranged at a direct right

angle to the second pair of depressions, substantially as and for the purpose set forth. 10

In testimony whereof I affix my signature in presence of two witnesses.

WILLIAM P. FORNFINNE.
